(57) **CLAIM**

The ornamental design for a bottle, as shown and described.

DESCRIPTION

FIG. 1 is a front view of a bottle showing my new design;
FIG. 2 is a rear view thereof;
FIG. 3 is a top view thereof;
FIG. 4 is a bottom view thereof;
FIG. 5 is a top-front perspective view thereof; and,
FIG. 6 is a bottom-rear perspective view thereof.
The broken lines in the drawing depict portions of the bottle
that form no part of the claimed design.
